UNITED STATES PATENT OFFICE.

WILLIAM H. BERSSENBRUGGE, OF MILWAUKEE, WISCONSIN.

ASH TRAY.

Application filed January 29, 1927. Serial No. 164,613.

This invention relates to ash trays.

Objects of this invention are to provide an ash tray which will cooperate with a standard card table in a novel and effective manner to temporarily lock the ash tray to the card table, so that the ash tray projects from the corner of the table and yet is held in a substantial and firm manner.

It is to be noted that card tables are not very extensive and usually their entire surface is utilized in a game of cards. The usual practice is to place an ash tray upon the top of the table, but this necessarily interferes with the freedom of the players.

This invention overcomes the defects noted above in that it provides an ash tray which does not occupy any of the available space on the card table, but which projects therefrom, as stated, and which is preferably set below the top of the table so as not to interfere in any manner with the freedom of the players.

Further objects are to provide a very simple type of ash tray having the characteristics enumerated above, which may be cheaply formed, and which may be very readily secured in place.

An embodiment of the invention is shown in the accompanying drawings in which:

Figure 1 is a plan view of the ash tray showing it attached and showing a portion of the card table;

Figure 2 is a sectional view through the ash tray on the line 2-2 of Figure 1, the table being shown in dotted lines;

Figure 3 is a sectional view on the line 3-3 of Figure 1.

Card tables, as usually constructed, are provided with a frame work 1 of rectangular formation to which is secured the top 2. A groove 3 is provided in the frame work and the edges of the cover 4 for the table top 2 and positioned within the groove. Further, it is the usual practice to reinforce the corner portions where two of the side frame members meet with an angular metal member 5 which is folded about such corner portion, and which has its upper edge folded into the groove 3 in the adjacent frame members 1.

The ash tray is so constructed that it cooperates with this standard card table construction and comprises a bowl or ash receiving portion 6 stamped from sheet metal and preferably provided with a rolled or beaded edge 7. This edge continues

throughout the major portion of the margin of the bowl or body portion of the ash tray and merges into a flat bearing portion 8, as may be seen from Figures 1 and 2. This flat bearing portion is provided with downwardly extending flanges 9 which run into the bead 7 or downwardly turned flange of the bowl and thus form a very rigid construction. The bearing portion 8 is flat and is provided with two downwardly turned lips 10 set at right angles to each other, as may be seen from Figure 1. These lips 10 are relatively short in extent and fit within the slots 3 formed in adjacent side frame members, as shown most clearly in Figures 1 and 3. Thus, a positive interlocking is secured between the ash tray and the card table.

In order to prevent the inadvertent upward lifting of the ash tray a spring finger 11 is pivotally secured as by means of a pivot 12 to the central bottom portion of the ash tray 6. Preferably, the spring finger 11 is provided with a curved outer end and is bowed intermediate its length so as to provide a bearing face 13 adapted to engage beneath the corner portion of the table, as shown in Figures 1 and 2.

In positioning the device, the lips 10 are slipped into the appropriate grooves 3, as shown in Figure 1, and the spring arm or retaining arm 11 is rocked about the pivot 12 into the position shown in dotted lines in Figure 1, and in full lines in Figure 2. This securely holds the ash tray against detachment from the table and makes a very firm construction.

When it is desired to remove the ash tray it is merely necessary to rock the locking arm 11 into the position shown in dot and dash lines in Figure 1 away from the corner of the table. Thereafter, the ash tray may be detached by lifting it directly upwardly from the table.

It is to be noted that the construction is such that the utmost rigidity is secured, although the ash tray may be formed from relatively thin sheet metal. The rolled marginal portion 7 runs into the side flanges 9 of the bearing member 8 and, consequently, produces a very rigid construction, in addition to the rigidity secured by the pressing of the bearing portion 8 upwardly and the shaping of the bowl or body portion of the ash tray.

Thus, an ash tray has been provided which

is eminently suited to card tables and which will rigidly and securely interlock with the card table and hold itself in an easily accessible position without wasting any of the 5 available space on the top of the table.

It will be seen further that the ash tray is of extremely simple and cheap construction and may be readily made and easily applied.

Although the invention has been described 10 in considerable detail, such description is intended as illustrative rather than limiting as the invention may be variously embodied and as the scope of such invention is to be determined as claimed.

15 I claim:

1. An ash tray comprising a body portion having a depression for the reception of ashes and having a bearing portion projecting therefrom, said bearing portion being 20 provided with downwardly extending lips adapted to engage the groove of a card table at spaced points, and means for preventing the upward lifting of the ash tray.

2. An ash tray comprising a body portion 25 having a depression for the reception of ashes and having a bearing portion projecting therefrom, said bearing portion being provided with downwardly extending lips adapted to engage the groove of a card table 30 at spaced points, and a spring arm pivotally secured to the underside of the body portion and adapted to be rocked beneath the corner of a card table.

3. The combination of a card table having a groove extending around its peripheral portion, an ash tray adapted to cooperate with the corner portion of the card table and comprising a depressed body portion, a bearing member provided with a pair of angularly arranged downwardly extending 40 fingers adapted to fit into the said groove, and a locking arm pivoted to the underside of the body portion of the ash tray and adapted to be swung beneath the corner portion of the card table. 45

4. The combination of a card table having a groove extending around its peripheral portion, an ash tray adapted to cooperate with the corner portion of the card table and comprising a depressed body portion, a bearing member provided with a pair of angularly arranged downwardly extending fingers 50 adapted to fit into the said groove, and a locking arm pivoted to the underside of the body portion of the ash tray and adapted to be swung beneath the corner portion of the card table, said ash tray having a peripheral downwardly extending flange, and said bearing member having downwardly extending side flanges merging into said first mentioned flanges. 55

In testimony that I claim the foregoing I have hereunto set my hand at Milwaukee, in the county of Milwaukee and State of Wisconsin.

WILLIAM H. BERSSENBRUGGE.
